UNITED STATES PATENT OFFICE.

HARRY E. MATHERS, OF DELTA, COLORADO.

CUTTING-MACHINE.

1,308,600.

Specification of Letters Patent.

Patented July 1, 1919.

Application filed January 5, 1918. Serial No. 210,559.

To all whom it may concern:

Be it known that I, HARRY E. MATHERS, a citizen of the United States, and resident of Delta, in the county of Delta and State 5 of Colorado, have invented certain new and useful Improvements in Cutting-Machines, of which the following is a specification.

The present invention has reference, generally, to cutting machines, and the invention 10 relates, more particularly, to an improved feed for cutting machine.

The invention has for its dominant object to provide a cutting machine having a movable carriage, which carriage is automatically advanced with each operation of 15 the cutting means, thus, advancing the material being cut or sliced thereby and insuring the cutting of predetermined quantities.

20 Another object of the invention is to provide novel means for automatically advancing the carriage previous to the cutting operation, the said means being movable independently of the cutting means, whereby, 25 the carriage may be returned subsequent to the cutting of the material as carried thereby and also allowing adjusting of the carriage, irrespective of the cutting means.

A further object of the invention is to 30 provide the carriage advancing means with means for varying the movement of the same and as a consequence, the movement of the carriage.

Among other aims and objects of the invention may be recited, the provision of a 35 device of the character mentioned with a view to compactness, and in which the number of parts are few, the construction simple, the cost of production small, and efficiency 40 and operation high.

Other improvements and novel details in the construction and arrangement of the various parts of the device will be brought out more in detail in the description to follow, 45 which for a clear understanding of the invention, should be considered in connection with the accompanying drawings forming parts hereof and wherein is disclosed for the purpose of illustration, a convenient and 50 satisfactory embodiment of the invention.

In the drawings:

Figure 1 is a side elevation of my improved cutting machine;

Fig. 2 is a top plan thereof;

55 Fig. 3 is a fragmentary front elevation of the machine;

Fig. 4 is a detail in elevation showing the mounting of the advancing pawl; and

Fig. 5 is a disassembled perspective of the same.

Similar characters of reference are employed in all of the above described views to indicate corresponding parts.

Referring now more specifically to the several figures of the said drawings, there 65 is provided a base 1, a portion of which is stepped as at 2 and has secured to its outer marginal edge thereof a retaining or guide plate 3, the plate being secured in position through the medium of screws or the like 4. 70

A post 5 is securely mounted upon the base 1 adjacent the stepped portion 2 thereof and pivotally supports a knife carrying arm 6, the knife designated 7 having the cutting edge thereof so arranged as to permit the 75 even engaging thereof with the surface of the material carrying and feeding carriage, which will be subsequently described. A metal strap 8 is secured to one side of the post 5 and receives a portion of the knife 80 carrying arm 6 therein, obviously, serving to prevent undue lateral movement thereof during its pivotal or cutting movement.

A material carrying and feeding carriage 9 is slidably arranged within the stepped 85 portion 2 of the base and has secured to one side thereof a ratchet bar 10, the teeth of which project slightly above the upper surface thereof.

A bracket 11 is secured to the base, parallel to the stepped portion 2 thereof and has its upper extremity provided with a receiving channel 12, whereby a block 13 having a plurality of openings therein may be slidably mounted upon the same. An angle 95 arm 14 is pivotally secured to the slidable block 13 adjacent one of the openings therein as at 15, while through the remaining opening, a pivot bolt 16 is passed which supports thereon, a pawl 17 having an upper extension thereon whereby a contractile spring 18 may be connected to the same and to a portion of the angle arm 14. Obviously, due to the engagement of the spring 18 with the pawl, the tooth thereof will be normally maintained in engagement with the teeth of the ratchet bar 10.

A curved arm 19 is pivotally mounted upon one side of the post 5, as at 20, and has one extremity thereof slotted as at 21, 110 whereby, the free extremity of the angle arm 14 may be pivotally and slidably con-

nected to the same through the medium of a bolt 22 carried thereby. A contractile coiled spring is secured at its upper end to the free end of the curved arm 19 and at its 5 lower end to the base 1 and affords means for normally holding the slidable block 13 in its retracted position, due to the engagement of the angle arm 14 therewith. To prevent undue downward movement of the 10 free extremity of the curved arm 19, a slotted abutment 24 is secured to the adjacent side of the post 5 and is engaged thereby at times.

It is to be noted, that the free extremity 15 of the curved arm 19 is arranged in the path of travel of the pivotal knife carrying arm and as a consequence, when the said arm is swung upwardly previous to the cutting operation, reciprocatory movement will be im- 20 parted by way of the curved arm 19 and angle arm 14 to the slidable block 13, thus, advancing the pawls 17 together with the slidable carriage 9. As the pivotal knife carrying arm is swung downwardly to cause 25 engagement of the knife 7 with the material, the slidable block 13 will be returned to its normal position within the channeled way 12, thus, reengaging the pawl 17 with the preceding tooth on the ratchet bar 10.

30 From the foregoing, it is evident, that with my improved cutting machine, the slid- 35 able carriage 9 will be automatically ad- vanced a predetermined distance, thus, in- suring the cutting of a predetermined quan- tity from the material arranged upon the carriage. Should it be desired to increase the amount of material cut by the machine, the bolt 22 carried upon the angle arm 14 may be loosened and adjusted within the slot 40 21 to vary the course of the angle arm 14 and the movement of the slidable block 13.

Manifestly, the construction shown is ca-

pable of considerable modification and such modification as is within the scope of my claims, I consider within the spirit of my 45 invention.

I claim:

1. A cutting machine including a base, a carriage slidable on said base carrying ratchet teeth adjacent one longitudinal edge 50 thereof, ratchet means slidably supported on the base engageable with said ratchet teeth, trip means adjustably connected to said ratchet means and normally held in a pre- determined position, and an arm disposed 55 transversely of the base and the carriage adapted to engage and actuate said trip member upon a raising of the arm.

2. A cutting machine including a base, a carriage slidable on said base having ratchet 60 teeth arranged thereon adjacent one longitudinal edge thereof, a bracket immovably supported on the base, a plate slidably mounted on the bracket, a pawl pivoted to the plate normally engaged with the ratchet 65 teeth on the carriage, a post arranged on the base, a curved arm pivoted to said post having its upper end arranged in a substan- tially horizontal plane, means for effecting 70 adjustable connection between the remaining end of the arm and said slidable plate for causing the same to be moved predetermined distances, said curved arm being normally held in a predetermined position to which it returns subsequent to operation, and a 75 knife carrying arm disposed transversely of the base and carriage and pivoted to said post, one portion of said arm being engage- able with the horizontal upper portion of the curved arm for actuating the same upon 80 raising of said arm.

In testimony whereof, I affix my signature hereto.

HARRY E. MATHERS.
